UNITED STATES PATENT OFFICE.

FREDERICK G. YAWMAN, OF ROCHESTER, NEW YORK.

COPY-HOLDER.

1,262,729.

Specification of Letters Patent. Patented Apr. 16, 1918.

Application filed July 2, 1917. Serial No. 178,186.

To all whom it may concern:

Be it known that I, FREDERICK G. YAWMAN, a citizen of the United States, and resident of Rochester, in the county of Monroe and State of New York, have invented 5 certain new and useful Improvements in Copy-Holders, of which the following is a specification.

The present invention relates to copy 10 holders and more particularly to the type in which a line guide and a work support are relatively movable so that successive lines on the work may be indicated by the line guide, an object of this invention being to provide 15 an improved means for effecting the relative movement between the line guide and the work support whereby any desired line spacing may be obtained and the moving part may be readily returned to its initial position. Another object of the invention is to 20 provide an improved means for absorbing the shocks due to the return movement of the moving part.

To these and other ends the invention 25 consists of certain parts and combinations of parts all of which will be hereinafter described, the novel features being pointed out in the appended claims.

In the drawings:—

30 Fig. 1 is a front view of a copy holder embodying the present invention;

Fig. 2 is a horizontal section through the copy holder;

35 Fig. 3 is an enlarged detail view of the elevating means of the copy holder;

Fig. 4 is a vertical section on the line 4—4, Fig. 3;

Fig. 5 is a vertical section on the line 5—5, Fig. 2; and

40 Fig. 6 is an enlarged sectional view showing the coöperation between the bumper at the upper portion of the stationary frame and the movable copy holder.

45 While the invention is herein illustrated as embodied in a construction in which the work support moves with relation to the line guide, it will be understood that I do not limit myself to this arrangement.

50 In the illustrated embodiment of the invention there is employed a stationary frame comprising preferably a base member 1 having guides 2 extending upwardly therefrom in parallel relation, said guides being in the form of rods, secured at their lower ends to the base member 1, and connected at their upper ends by a cross-piece 3, the latter being

formed from sheet metal and rolled at its ends to form tubes 4 surrounding reduced portions 5 at the upper end of the rods 2. The lower edge of this cross-piece 3 is bent 60 rearwardly at 6, and has a swinging member 7 pivoted thereto at 8 and extending in rear of the frame. A second member 9 is pivoted to the member 7 at 10, and has a line guide 11 pivoted thereon at 12, the 65 member 9 being arranged to lie in front of the stationary frame so as to position the line guide in front of said frame.

Operable on the stationary frame is the 70 movable work support 13, the latter preferably being formed from sheet metal and having its opposite edges rolled at 14 to provide guides operating on the guide rods 2. A work clamping device 15, which is not herein claimed but forms the subject matter 75 of another application, is arranged at the upper portion of the work support 13, while a loop 16 is provided at the upper end of the work support for securing those leaves of the work which are swung upwardly over 80 the edge of the work support.

The mechanism for producing a relative movement between the work support and the line guide, in this instance, embodies an operator 17 preferably in the form of a hand 85 wheel on a shaft 18, which is mounted to turn within the forward extension 19 on the base member 1. At its rear end, the shaft 18 is provided with a friction gear wheel 20, the latter engaging within the 90 grooved periphery of a friction gear wheel 22 which is journaled on a stub shaft 23 arranged on the base member 1 in rear of the guides 2. Connection between the friction wheel 22 and the work support 13 is prefer- 95 ably established by a flexible connector 24, in this instance in the form of a tape piece about the friction wheel 22 preferably in the groove of the latter and extending from said wheel upwardly over a grooved pulley 100 25 journaled at 26 in the upper portion of a hollow standard 27, which projects upwardly from the base member 1 between the guides 2. From the pulley 25 the flexible connector 24 leads to and is connected with a bracket 105 28 which is secured to the rear face of the work support 13 near the lower edge of the latter. It is apparent that when the operator 17 is turned in the direction of the arrow, Fig. 1, the tape 24 will be wound on the drum and friction wheel 22, and will ele- 11 vate the work support 13.

With the object in view of preventing the descent of the work support 13 except when desired, the shaft 18 carries a toothed wheel 29 with which coöperate two pawls or dogs 30 and 31 mounted to turn on a common axis formed by a screw bolt 32 secured in the stub shaft 23. The respective teeth 33 and 34 of the dogs 30 and 31 are located at different distances from the common pivot of the dogs, so that the dogs alternately engage the ratchet wheel 29, thus permitting the work support to partake of a finer adjustment than would be possible with only one dog.

15 To permit the descent of the work support 13 the friction wheels 20 and 22 act as a make-and-break, motion-transmitting connection between the work support and the rotary operator 17, and to this end one 20 of said wheels has a movement transversely of its axis relatively to the other wheel. This is accomplished, in this instance, by laterally widening the bearing at the inner end of the shaft 18, as at 35 Fig. 5. Normally 25 the shaft 18 is held toward the friction wheel 22 by a spring 36 which is, in this instance, formed of a coil secured at one end at 37 to the shaft 18, and at the other end to the screw 32. The lowering of the work 30 support is effected by attempting to turn the operator 17 counterclockwise, or in a direction opposite that of the arrow shown in Fig. 1. This causes the shaft 18 to move laterally in the bearing enlargement 35, due 35 to the engagement of one of the teeth 33 or 34 coöperating with the toothed wheel 29 and acting as a fulcrum. With the lateral movement of the shaft 18, the friction wheel 22 is freed and the work support 13 40 descends under its weight. This descent may be stopped at any time by releasing the operator 17 to permit the spring 36 to throw the friction wheel 20 into contact with the friction wheel 22.

45 Retardation of the descent of the work support 13 may be effected by a spring 38 preferably in the form of a volute coil arranged within the drum or friction wheel 22, and having its inner end secured at 39 50 to said wheel, and its outer end secured at 40 to a screw which is fixed in the base member 1. A cover plate 41 may be employed for inclosing the spring within the drum or friction wheel 22, said cover plate 55 being held against rotation by the screw 40, and at the same time surrounding the stub shaft 23.

To prevent jar at the extreme lower limit of the work support, the stationary frame 60 is preferably provided with two buffers, in this instance, in the form of rubber pieces 42 fitted in the upper ends of tubes 4 of the cross piece 6, so as to coöperate as the latter reaches the lower limit of its movement with 65 a bead or abutment 43 situated on the rear

face of the work support near the upper edge of the latter.

From the foregoing it will be seen that there is provided a copy holder in which the elevating means is controlled by an operator 70 which is rotated in but one direction, said operator having a second movement to release the work, the operator being secured to a rotary shaft which is shifted laterally on said second movement of the operator to 75 throw two gears out of coöperation. Counterbalancing means for the moving part is connected to one of said gears, and buffers are arranged so that an effective stop of the work support is secured without any 80 rebound.

The feature of providing a make-and-break, motion-transmitting connection between a rotary operator and the moving part of the copy holder controlled by the rotary 85 operator is not claimed broadly herein, but forms the subject matter of an application filed by me on April 17, 1916, Serial No. 91,584.

What I claim as my invention and desire 90 to secure by Letters Patent is:—

1. In a copy holder having a work support and a line guide; means for effecting relative movement between the work support and the line guide comprising two co-operating rotary gears, means for holding one of said gears from turning in one direction, means connecting the other gear to the moving part, and means for supporting said first-named gear so that it may move 100 laterally of its turning axis out of connection with the other gear to permit the moving part to return to its initial position.

2. In a copyholder having a work support and a line guide; means for effecting 105 relative movement between the work support and the line guide comprising a rotary operating shaft having a transverse movement, and a make-and-break, motion-transmitting connection between the moving 110 part of the copy holder and the rotary shaft, controlled by the transverse movement of the shaft.

3. In a copy holder having a work support and a line guide; means for effecting 115 relative movement between the work support and the line guide comprising a rotary shaft having a transverse movement, a ratchet on the shaft, a pawl coöperating with the ratchet and mounted independently of 120 the shaft, and a make-and-break, motion-transmitting connection between the moving part of the copy holder and the shaft, controlled by the transverse movement of the shaft produced through the engagement of 12 the pawl on the reversing of the rotation of the shaft.

4. In a copy holder having a work support and a line guide; means for effecting 13 a relative movement between the work sup-

port and the line guide comprising a rotary operator, a shaft on which said operator is mounted having a transverse movement at one end, a ratchet wheel on the shaft, a pawl mounted independently of the shaft and engaging the ratchet wheel, a gear on the shaft, and a gear independently mounted, connected to the moving part of the copy holder and adapted to be disengaged by the gear on the shaft when the latter is moved laterally with the shaft.

5. A copy holder as set forth in claim 4 combined with a spring normally tending to resist the transverse movement of the shaft to hold the two gears in coöperation.

10. In a copy holder having a work sup-

port and a line guide; means for effecting relative movement between the work support and the line guide comprising a flexible connector secured to the moving part, a 20 grooved wheel in which said flexible connector is wound, and a gear adapted to frictionally engage the side walls of the grooved wheel for turning the latter to wind the flexible connector thereon.

25

7. A copy holder comprising a stationary frame, a work support guided vertically on the frame, a bumper arranged at the top of the stationary frame and an abutment on the work support at a point nearer the top 30 of the work support than the bottom.

FREDERICK G. YAWMAN.
